UNITED STATES PATENT OFFICE.

LOYD R. STOWE, OF MAPLEWOOD, MISSOURI.

STOKER.

Application filed July 17, 1919. Serial No. 311,455.

To all whom it may concern:

Be it known that I, Loyd R. Stowe, a citizen of the United States, residing at Maplewood, in the county of St. Louis and 5 State of Missouri, have invented certain new and useful Improvements in Stokers, of which the following is a specification.

This invention relates to improvements in automatic stokers and its purpose is to provide a stoker of the chain grate type in 10 which a plurality of independent sets of fuel feeding devices are actuated to maintain a substantially uniform thickness of fuel over the grate while at the same time securing a 15 positive feed of the fuel. The principal object of the invention is to provide a chain grate stoker having a plurality of independent sets of grate chains which are actuated simultaneously but at different speeds. A 20 further object is to provide a grate having two series of chains arranged with their upper surfaces in different planes in order to regulate the speed of travel of the fuel and to build up the fuel bed adjacent the 25 discharge end of the grate, thereby overcoming a defect which is present in chain grates of the usual type. Another important feature of the invention is the provision of improved means for supporting and 30 actuating the grate chains.

These and other objects will be understood more fully from the following specification taken with the accompanying drawings in which one embodiment is illustrated.

35 In the drawings:

Fig. 1 shows the top plan view of the furnace structure with the grate chains removed;

Fig. 2 shows side elevation of the furnace 40 with the side wall of the furnace removed, the position of the chains being shown diagrammatically;

Fig. 3 shows a longitudinal sectional view on the line 3—3 of Fig. 1;

Fig. 4 shows a transverse sectional view on the line 4—4 of Fig. 2;

Fig. 5 shows a transverse sectional view on the line 5—5 of Fig. 3;

Fig. 6 shows a transverse sectional view on the line 6—6 of Fig. 3;

Fig. 7 shows a transverse sectional view on the line 7—7 of Fig. 3;

Fig. 8 shows a partial perspective view of one of the side frames of the stoker;

55 Fig. 9 shows a perspective view of one of the skids by which the upper stretches of

the chains are supported between the upper and lower ends of the grate,

Fig. 10 is a perspective view of a modified form of skid which is located above the 60 center frame; and

Fig. 11 is a plan view of a portion of the grate chains.

In the accompanying drawings the stoker is shown mounted on a foundation 15 of concrete or the like which comprises an upper ledge or step 15^a at the forward end of the stoker, a lower ledge 15^b at the rear thereof, and an upwardly extending abutment 15^c at the rear end of the grate. The foundation 70 is provided with a conduit 16 having a gate valve 17 located therein to control the supply of compressed air to the under side of the grate. A vertical extending fire brick bridge wall 18 is located at the rear end of the grate and the ash pit 19 is located between the bridge wall and the rear end of the foundation 15. The stoker is located between the usual side walls 20 of fire brick 75 or the like.

The stoker mechanism is supported primarily by a pair of side frames 22 which are supported on the ledges 15^a and 15^c of the foundation and provided with upwardly extending plates 22^a at the forward end of the furnace. An ignition arch 23 is located above the grate at the forward end of the furnace member and the fuel is supplied to the grate from a hopper 24 which is located between the parts 22^a of the side frame at 80 the forward end of the ignition arch. The hopper has an inclined lower wall 25 and the discharge of fuel through the outlet opening 26 is regulated by a vertically adjustable gate 27. A sheet metal end wall 28 extends between the side frames at the forward end of the stoker to inclose the stoker mechanism and confine the air blast which is supplied to the under side of the grate.

The stoker mechanism comprises two series of grate chains 30 and 31, the chains of one series being arranged to alternate with those of the other series across the furnace. At the upper or forward end of the stoker the chains 30 are mounted on sprocket gears 32 which are secured to the transverse shaft 33. This shaft is journaled in bearings 34 carried by the side frame members 22 and is actuated by a worm wheel 35 secured to the 105 projecting end thereof at one side of the stoker. The worm wheel 35 is actuated by 110

a worm 36 secured to a shaft 37 journalled in the bracket members 38 carried by the plate 22^a. A ratchet wheel 39 is secured to the shaft 37 and is actuated by a pawl 40 which is pivoted on one arm of a bell-crank lever 41. The other arm of this lever is connected with an operating rod 42 which may be actuated by any desired mechanism in order to rotate the ratchet wheel and thereby drive the shaft 33 and the chains 30 which are operated thereby.

The other chains 31 are mounted at the forward end of the furnace on other sprocket gears 44 which are rotatably mounted on the shaft 33. The sprocket gears 44 having gears 45 formed integrally therewith and these gears 45 are adapted to mesh with driving pinions 46 which are secured to a transverse shaft 47 located between the upper and lower stretches of the chains 30 and 31. The shaft 47 is journalled in bearings 48 carried by the side frames 22 and one end of this shaft extends beyond the side frames at the side of the furnace opposite the worm wheel 35. This projecting end of the shaft 47 carries a fixed worm wheel 49 which is driven by a worm 50 mounted on a shaft 51. The shaft 51 is journalled in brackets 52 carried by the adjacent side frames 22 and it is driven by a ratchet wheel 53 which is adapted to be engaged by a pawl 54 mounted on one arm of the bell-crank lever 55. The other arm of this lever is connected to an operating rod 56 which is adapted to be operated simultaneously with the previously described rod 42 but at a different speed so that the chains 31 driven by the shaft 47 have a different speed of travel than the chains 30 driven by the shaft 33. At the lower end of the grate the chains 30 and 31 are mounted on sprocket gears 60 and 61, respectively, which are adapted to rotate on a transverse shaft 62 carried in bearings 63 formed in side frames 22.

The shaft 33, 47, and 62 are supported by the side frames and by one or more center frames 65 which have the form illustrated particularly in Fig. 3. The center frame 50 rests upon the ledges 15^a and 15^b of the foundation and is supported at an intermediate point by a post 66 which extends downwardly to the portion 15^b of the foundation. At the forward end of the stoker 55 the center frame extends upwardly and is provided with bearings 67 and 68 for the under side of the shafts 33 and 47, respectively, this upwardly extending portion of the center frame being adapted to project 60 between two of the chains 30 and 31 as illustrated in Fig. 4. At the lower end of the furnace the center frame is provided with an upwardly extending part 69 which is provided with a bearing for the shaft 62 65 and which extends upwardly and conforms

to the upper end surfaces of the grate for the purpose of closing the space between the two chains 30 and 31 which are spaced apart to receive the center frame.

The upper stretches of the chains 30 and 31 are supported between the upper and lower ends of the grate by means of plates or skids 70 which are carried by transverse supporting beams 71. These beams are secured at their ends to the side frames 22 and at their middle points they are secured to the upper flange of the center frame 65. The skids 70 are substantially T-shaped in cross section as shown in Fig. 6, 7, 9, and 10, being provided along their upper edges with two laterally extending flanges 70^a and 70^b while the lower transverse flanges 70^c are secured to the transverse beams 71. The flanges 70^a and 70^b carried by each skid lie in different planes which intersect each other between the upper and lower ends of the grate. The flange 70^a carried by one skid is adapted to cooperate with a similar flange 70^a carried by the adjacent skid for supporting one of the chains 31. At the upper end of the grate the flanges 70^a are located above the flanges 70^b, thereby causing the chains 31 to project above the chains 30 in the upper part of the grate. At the point where the planes of the flanges 70^a and 70^b intersect, the chains 30 and 31 are on the same level as shown in Fig. 6. In the lower part of the grate the flanges 70^b lie above the flanges 70^a so that the chains 31 in this area of the grate lie below the chains 30. The chains 30 adjacent the side frames 22 are supported partially by inclined flanges 73 which conform to the contour and inclination of the flanges 70^b. In addition to the provision of means for causing the upper surfaces of the chains 30 and 31 to lie in different planes, the skids 70 are curved upwardly toward the lower end of the grate so that the upper surfaces of the grate chains have a lesser inclination to the horizontal adjacent the bridge wall than they have in the upper part of the grate. The side frames 22 and the center frame 65 are similarly curved to accommodate the curvature of the upper surfaces of the grate. One of the skids 70 which is located directly above the center frame 65 is provided with an upwardly extending flange 75 which extends into the space between the chains 30 and 31 which are spaced apart on account of the center frame at the middle part of the grate. This flange extends rearwardly at the lower end of the grate as shown at 75^a and meets the upwardly extending part 69 of the center frame.

A baffle-plate 76 extends transversely of the furnace between the lower ends of the skids 70 and the sprocket gears 60. This baffle-plate is mounted to rock on a transverse rod 77 secured to the side frames and the

lower curved extremity 76^a thereof is adapted to ride upon the lower stretches of the chains 30 and 31 above the transverse abutment 15. The chains 30 and 31 are each formed of a plurality of groups of links 78 which are connected by transverse pins 79 and bushings 79^a and the inner links of each group are cut away on their inner sides to form recesses 30^a and 31^a to receive the sprocket gears 32, 44, and 60 upon which the chains are mounted. The lower curved portion 76^a of the baffle-plate 76 is provided with depending flanges 76^b which are adapted to engage the recesses 30^a and 31^a of the grate chains. The baffle-plate and the parts thereof which cooperate with the chain thus prevent the flow of compressed air from the chamber beneath the grate into the ash pit 19. The draft of the furnace is thus confined and compelled to flow through the apertures in the chains which are formed by grooves 80 in the sides of the links 78. After passing the abutment 15^c and the baffle-plate 76, the lower stretches of the chains 30 and 31 are supported on tubular rollers 82 which are adapted to rotate on rods 83 extending between each of the side frames and the center frame 65.

In the operation of the stoker the fuel is discharged from the hopper 24 onto the upper end of grate and is then moved downwardly by the action of chains 30 and 31. Since the chains 31 project above the chains 30 in the upper part of the grate, it will be apparent that the chains 31 will have a greater effect in feeding the fuel in the upper area of the stoker and in order to secure a relatively rapid feed of the fuel at this point, the chains 31 are preferably actuated at a greater speed than the chains 30, this being accomplished through suitable operation of the mechanism by which the shaft 33 is driven. Toward the lower end of the grate the chains 31 are depressed below the chains 30 thus permitting the latter chains which move at a lower speed to have a greater influence in controlling the rate of feed of the fuel. This results in a retardation of the fuel adjacent the discharge end of the grate so that the thickness of the fuel bed is built up adjacent the bridge wall. The effect of the difference in speed of the two sets of chains and of the difference in elevation of the upper surfaces thereof in retarding the fuel toward the lower end of the grate, is augmented by the curvature of the upper grate surface. The body portion of the grate surface preferably has a general inclination which approximates the angle of repose but in practice it is found that an angle of about 20° to the horizontal is satisfactory for the body portion of the grate depending upon the conditions of operation and the fuel used. This inclination is decreased toward the lower end of the grate in order to effect a retardation of the fuel and to prevent the discharge of the fuel over the lower end of the grate until it has been completely consumed. By means of the construction herein described it is possible to maintain a proper regulation of the rate of the fuel feed in all parts of the area of the grate and to maintain that condition of the fuel bed which is most suitable for a proper composition of the fuel. The construction of the grate and the arrangement of the upper stretches of the chains also effects an agitation of the fuel to break up clinkers and prevent the formation thereof thereby maintaining an open and porous condition of the fuel bed.

Although I have shown and described a single embodiment of the invention for purposes of illustration it will be understood that it may be constructed in various other forms without departing from the scope of the appended claims.

I claim:

1. The combination in a stoker of a grate comprising two series of grate chains, the upper surface of the chains of one series lying in a plane different from the plane of the upper surface of the chains of the other series, the chains of one series being arranged to alternate laterally across the grate with the chains of the other series.

2. The combination in a stoker of two series of grate chains, the chains of one series being arranged to alternate laterally across the grate with the chains of the other series, the upper surfaces of the chains of one series projecting above the upper surfaces of the chains of the other series.

3. The combination in a stoker of two series of grate chains, the chains of one series being arranged to alternate laterally across the grate with the chains of the other series, the upper surfaces of the chains of one series projecting above the upper surfaces of the chains of the other series, and means for actuating the chains of one series independently of the chains of the other series.

4. The combination in a stoker of two series of relatively narrow grate chains, the chains of one series being arranged to alternate laterally across the grate with the chains of the other series, the upper surfaces of the chains of one series lying in a different plane than the upper surfaces of the chains of the other series, and means for simultaneously and continuously actuating the chains of each series, the chains of one series being operated at a different speed than the chains of the other series.

5. The combination in a stoker of two independent series of grate chains mounted on an incline with the chains of one series arranged in alternation laterally across the grate with the chains of the other series, the upper surface of the chains of one series

lying in a different plane than the chains of the other series, said planes intersecting each other between the ends of the grate.

6. The combination in a stoker of two independent series of grate chains, the chains of one series alternating with the chains of the other series, and having their upper surfaces in a plane that intersects the plane of the upper surfaces of the chains of the other series.

7. The combination in a stoker of a series of grate chains spaced apart, a second series of grate chains each located in the space between two of said first named chains, means for supporting the chains of one series so that the upper stretches thereof lie in a plane different from the plane of the other series, and means for actuating the chains of one series independently of the chains of the other series.

8. The combination in a stoker of a series of grate chains spaced apart, a second series of grate chains each located in the space between two of said first named chains, said first named chains projecting above said second named chains at the forward end of the grate and extending below said first named chains toward the rear end of the grate, and actuating means for causing said first named chains to move at greater speed than said second named chains.

9. The combination in a stoker of a series of grate chains spaced apart, a second series of grate chains each located in the space between two of said first named chains, said chains being mounted on an incline with the lower portions thereof having a lesser inclination than the upper parts thereof, and means for actuating the chains of one series independently of the chains of the other series.

10. The combination in a stoker of a series of grate chains spaced apart, a second series of grate chains each located in the space between two of said first named chains, said chains being mounted on an incline with the lower portions thereof having a lesser inclination than the upper parts thereof, the chains of one series being arranged with their upper surfaces lying in a different plane than the chains of the other series, and means for actuating the chains of each series.

11. The combination in a stoker of a series of grate chains spaced apart, a second series of grate chains each interposed in the space between two of said first named chains, said chains being mounted on an incline, means for supporting said chains with the upper surfaces of those of one series projecting above the upper surfaces of those of the other series adjacent the upper part of the grate and extending below the upper surfaces of those of the other series adjacent the lower end of the grate, said chains having a

lesser incline adjacent the lower part of the grate, and means for actuating the chains of each series independently of the chains of the other series.

12. The combination in a stoker of a series of endless grate chains spaced apart, a second series of grate chains each interposed in the space between two of said first named chains, a series of skids underlying said chains and supporting the upper stretches thereof with the upper surfaces of the chains of one series lying in a different plane than the upper surfaces of the chains of the other series, and means for actuating the chains of each series independently of the chains of the other series.

13. The combination in a stoker of a series of grate chains spaced apart, a second series of chains each located in the space between two of said first named chains, a series of skids located between the upper and lower stretches of said chains and having flanges adapted to support the upper stretches of said chains, the flanges which support the chains of one series lying in a plane which intersects the plane of the flanges which support the chains of the other series, and means for actuating the chains of each series.

14. The combination in a stoker of a pair of side frames, transverse shafts extending between said side frames, two series of endless chains supported by said shafts and arranged with those of one series alternating with those of the other series, transverse beams extending between said side frames between the upper and lower stretches of said chains, and skids supported by said beams and having parts engaging said chains to support the upper stretches of those of one series in a different plane than the upper stretches of those in the other series.

15. The combination in a stoker of a pair of side frames, transverse shafts extending between said side frames, two series of endless grate chains supported by said shafts and arranged with those of one series alternating with those of the other series, transverse beams extending between said side frames between the upper and lower stretches of said chains, skids supported by said beams and having parts engaging said chains to support the upper stretches of those of one series in a different plane than the upper stretches of those in the other series, and a center frame interposed between two of said chains for supporting said transverse beams and extending downwardly therefrom to the foundation of the stoker.

16. The combination in a stoker of a pair of side frames, a shaft extending between said side frames at the forward end of the stoker, a series of sprocket gears fixed to said shaft, a second series of sprocket gears each rotatably mounted on said shaft between two of said first named sprocket gears, a series

of endless chains mounted on said first named series of sprocket gears, a second series of endless chains mounted on said second named series of sprocket gears, a second shaft extending between said side frames at the rear end of the stoker, a plurality of sprocket gears rotatably mounted on said second named shaft and supporting the rear portions of said chains, a series of gears each secured to one of said second named sprocket

gears, a driving shaft extending between said side frames, a series of pinions secured to said driving shaft and meshed with said gears, means for actuating said driving shaft, and means for actuating said first ¹⁵ named shaft.

In testimony whereof, I have subscribed my name.

LOYD R. STOWE.
